UNITED STATES PATENT OFFICE.

HARRIE A. BALLARD, OF BOSTON, MASSACHUSETTS, ASSIGNOR TO THE BOYLSTON MFG. COMPANY, OF SOUTH BOSTON, MASSACHUSETTS, A CORPORATION OF NEW JERSEY.

THREAD-CLAMP FOR SHOE-SEWING MACHINES.

1,127,719.

Specification of Letters Patent.

Patented Feb. 9, 1915.

Application filed January 28, 1909. Serial No. 474,669.

To all whom it may concern:

Be it known that I, HARRIE A. BALLARD, of Boston, in the county of Suffolk and State of Massachusetts, have invented certain new and useful Improvements in Thread-Clamps for Shoe-Sewing Machines, of which the following is a specification.

This invention relates to shoe sewing machines, and has for its object to provide 10 thread-locking means in connection with a presserfoot adapted to automatically compensate for sudden variations in the thickness of the work by supplying a relatively greater quantity of thread for an increasing 15 thickness of work, and a correspondingly smaller quantity of thread for a decreasing thickness of work. The invention is embodied in a pair of coöoperative members adapted to clamp the thread between the 20 needle and supply, said members being mounted upon a lever which carries a presserfoot, these clamping members are therefore moved by said lever toward and from a thread guide in accordance with variations in the thickness of the work. The 25 clamping members are moved toward the thread guide when the thickness of the work increases, and away from the thread guide when the thickness of the work decreases, 30 thereby giving up or drawing back a quantity of the needle thread. The effect of so arranging and actuating the thread clamping members is to eliminate to a greater extent the liability of breaking the needle 35 thread.

Of the accompanying drawings which illustrate one form in which the invention may be embodied, Figure 1 represents a left side elevation of the operating head of a 40 shoe-sewing machine equipped with thread-clamping members constructed and arranged in accordance with this invention. Fig. 2 represents a front elevation of a shuttle casing containing a rotary shuttle, 45 and a stationary work rest. Fig. 3 represents a fragment of the stitch-forming mechanism in the position in which the shuttle is in the act of taking a newly formed loop of thread. Fig. 4 represents a 50 vertical section through the head. Fig. 5 represents an elevation of the means for actuating the thread-clamping members.

The same reference characters indicate the same parts wherever they occur.

55 In order to explain the adaptation of the

present invention to a shoe-sewing machine, it may be stated that the machine herein illustrated comprises a head or frame 10, a cam shaft 11 journaled therein and stitch-forming mechanism including a needle 12, 60 an awl 13, a rotary shuttle 14, a looper 15, a thread finger 16, a loop spreader 17, their actuators hereinafter described and other necessary instrumentalities.

The needle thread α may be drawn from 65 any suitable source of supply preferably at the rear of the machine and passes over a tension device 18 and suitable take-up rolls 19, 20 and 21 before engaging the needle. The take-up roll 21 in this form of machine 70 is mounted on the free end of an oscillatory arm 60 while the take-up roll 20 is relatively stationary though preferably yielding, and the roll 19 which is in effect merely a guide roll is preferably stationary and mounted 75 upon a stud extending from the frame. 22 represents a stationary work rest and 23 represents a presserfoot movable toward and from the work rest and adapted to co-operate therewith in clamping the work α as 80 shown by Fig. 3. The presserfoot is mounted upon a lever 24 having a fulcrum at 25, and is normally forced toward the work rest by means of a spring 26 of which one end is connected to a fixture and the 85 other end to the rear of the presserfoot lever. By this means continual pressure of the presserfoot upon the work is maintained, and this is preferably rendered positive or non-yielding during the operation of the 90 stitch-forming mechanism by any suitable means which need not be described. It will be sufficient to state that the presserfoot lever is adapted to yield during the feeding 95 of the work.

The needle and awl are mounted respectively upon a needle carrier 27 and an awl carrier 28. These carriers are here shown as adapted to oscillate about a common axis 29, but the awl carrier is adapted to move 100 longitudinally of its axis for the purpose of feeding the work to the needle. For this purpose the awl carrier is mounted upon an arm 30, see Fig. 4, which extends forwardly from a reciprocating carriage not shown, but which is adapted to be actuated by means of a lever 31 coöperating with an appropriate cam upon the cam shaft 11. The thread clamping members are arranged 105 so as to clamp the thread between the ten- 110

sion 18 and the guide roll 19 as shown by Figs. 1 and 4. These members comprise a grooved roll 32 over which the thread is adapted to pass, and a complementary sliding member 33 adapted to coöperate therewith to clamp the thread. The roll 32 and slide 33 are mounted upon the presserfoot lever 24 at the rear of the fulcrum 25, and are adapted by reason of such arrangement to move toward the roll 19 when the presserfoot is moved away from the work rest, and on the other hand to move away from the roll 19 when the presserfoot is moved toward the work rest. The effect of such movement of the thread clamping members is to give an additional quantity of thread to the needle when the presserfoot is moved away from the work rest, and to take away a quantity of thread from the needle when the presserfoot is moved toward the work rest.

The slide 33 is mounted in guides 34 and is provided with a stud or projection 35 which occupies a slot 36 formed in an arm 37. The slot 36 is curved so that, when the arm is in the position shown, it is concentric with relation to the fulcrum 25 in order to enable the presserfoot lever to move about its fulcrum without disturbing the relation of the slide 33 with its complementary clamping member 32. The arm 37 is affixed upon a rock shaft 38 which has a suitable bearing in the head or arm 10. The rock shaft 38 is also provided with an arm 39 by which it is automatically actuated. The arm 39 has in its free end a cam roll 40 which occupies a groove 41 formed in a cam disk 42 mounted on the shaft 11. The width of the groove 41 is considerably greater than the diameter of the roll 40 for the purpose of permitting movement of the roll independently of the cam for a purpose hereinafter explained. The arm 39 is one arm of a lever which has an oppositely extending arm 43. A spring 44 contained in the socket 45 on the frame 45 engages the arm 43 and forces it in a direction tending to hold the cam roll 40 in engagement with the outer wall of the groove 41. The roll 40 however is so adjusted that it is prevented from engaging the outer wall 50 of the groove, with the exceptions herein-after stated, by reason of the coöperative engagement of the clamping member 33 with the member 32. For the purpose of retracting the member 33 so as to release the thread, the outer wall of the groove 41 is provided with cam portions 46 and 47 which are adapted to engage the roll 40.

Referring now to the stitch-forming mechanism, the operations of the shuttle 14, the looper 15, the thread finger 16 and the loop spreader 17 may be briefly described. The shuttle is contained in a shuttle race 48 in which it is driven continuously in the direction of the arrow shown in Fig. 2. The shuttle race is cut away at the point nearest

the needle so as to provide for the entrance of a loop *b* of needle thread into the path of the nose 49 of the shuttle. The shuttle is driven by a finger 50 on the forward end of a shaft 51 which may be driven by any appropriate means on the cam shaft 11. The looper 15 is mounted upon a carrier 52, (see Fig. 1), and is actuated so as to lay the thread *a* about the barb of the needle when the needle extends through the work so that its barb is below the work rest 22. The thread finger 16 is initially in front of the needle thread between the looper and the work rest, and is movable from front to rear for the purpose of drawing a quantity of thread from the take-up which it subsequently gives back to the needle while the latter is receding to draw the thread through the work. The thread finger is at one end of a slide 53 which has a pin and slot connection with a lever or actuator 54 arranged in coöperative engagement with a suitable cam on the shaft 11. The loop spreader 17 is at the free end of an arm 55 mounted upon a rock shaft 56. The rock shaft carries an arm 57 at the free end of which is a roll 58 adapted to engage the periphery of the cam disk 42. A spring 156 acting on the rock-shaft 56 serves to keep the roll 58 in engagement with the cam which has a bulging portion 59. The portion 59 imparts movement to the loop spreader 17 which causes the latter to enter a newly formed loop being drawn upwardly by the needle. The loop spreader opens the loop as shown by Fig. 3, so as to enable the nose of the shuttle to enter therein and take the loop for the purpose of interlocking the same with a locking thread presumably contained in a bobbin in the shuttle.

The shuttle is employed to set the stitch and then to draw out sufficient thread for the next stitch, and the thread lock is therefore closed to lock the thread during the first portion of the thread-pulling movement of the shuttle after which it is opened by the cam portion 46 to release the thread as the shuttle completes its thread-pulling movement. In view of this operation, the take-up lever 60 is not depended upon to set the stitch, but is employed for taking up the slack in the needle thread as it is released by the shuttle. The cam portion 46 does not engage its roll 40 until the preceding stitch has been set by the thread-pulling movement of the shuttle, but it does engage the roll so as to release the thread before the nose of the shuttle reaches its highest point. After this releasing of the thread, the remaining upward movement of the nose 49 has the effect of drawing an additional supply of thread for the next stitch, and after the shuttle has passed its highest point, the take-up arm 60 is actuated so as to draw off the excess thread for the next stitch. The

5 arm 43 is extended sufficiently to form a handle by which the rock shaft 38 may be manually moved for the purpose of retracting the clamping member 38 at any time it should be desired to so release the thread.

10 Having thus explained the nature of the invention, and described a way of constructing and using the same, although without attempting to set forth all of the forms in which it may be made, or all of the modes 15 of its use, I declare that what I claim is:—

15 1. In a sewing machine of the character described, stitch-forming mechanism, a presserfoot carrier, a thread lock arranged to be moved back and forth by said carrier to give up and take back thread on the increase and decrease, respectively, of the thickness of the work, and means arranged to operate the said thread lock to lock and release the 20 thread, said means being arranged to keep the thread lock in release position for as long a time for thin work as for thick work.

25 2. In a sewing machine of the character described, stitch-forming mechanism, a presserfoot carrier, a thread lock arranged to be moved back and forth by said carrier to give up and take back thread on the increase and decrease, respectively, of the thickness of the work, and means arranged 30 to operate said thread lock to lock and release the thread, said means being arranged to keep the thread lock in locking position for as long a time for thick work as for thin work.

35 3. In a sewing machine of the character described, stitch-forming mechanism, a presserfoot carrier, a thread lock arranged to be moved back and forth by said carrier to give up and take back thread on the increase and decrease, respectively, of the thickness of the work, and means arranged 40 to operate said thread lock to lock and release the thread, said means being arranged to maintain uniform timing of the thread lock regardless of the position of the latter.

45 4. In a sewing machine of the character described, stitch-forming mechanism, a presserfoot carrier, a thread lock arranged to be moved back and forth by said carrier to give up and take back thread on the increase and decrease, respectively, of the thickness of the work, and means arranged 50 to operate said thread lock to lock and release the thread, said means being arranged to keep the thread lock in locking position 55 the same length of time in successive cycles, regardless of the position of the thread lock.

5. In a sewing machine of the character described, stitch-forming mechanism, co-

active thread-clamping members, means arranged to move one of said thread-clamping members toward and from the other to clamp and release the thread, and means arranged to move said thread-clamping members to give up and take back thread on the increase and decrease, respectively, of the thickness of the work, the first-mentioned means being arranged to clamp the thread at the same relative stage in successive cycles regardless of the position of said clamping member.

6. In a sewing machine of the character described, stitch-forming mechanism, co-active thread-clamping members, means arranged to move one of said thread-clamping members toward and from the other to clamp and release the thread, and means arranged to move said thread-clamping members to give up and take back thread on the increase and decrease, respectively, of the thickness of the work, the first-mentioned means being arranged to release the thread at the same relative stage in successive cycles regardless of the position of said clamping member.

7. In a sewing machine of the character described, stitch-forming mechanism, a work support, a presserfoot and carrier therefor, a spring arranged to act on said carrier to keep said presserfoot against the work, a thread lock carried by said carrier and thereby movable to give up and take back thread on the increase and decrease, respectively, of the work, a member arranged to operate said thread lock, and means connecting said operating member and thread lock to preserve uniform timing of said thread lock by compensating for different positions of the latter.

8. In a sewing machine of the character described, stitch-forming mechanism, a presserfoot carrier, a thread lock arranged to be moved back and forth by said carrier to give up and take back thread on the increase and decrease, respectively, of the thickness of the work, and means arranged to operate said thread lock to lock and release the thread, said means being arranged to time the operation of said thread lock independently of variations in the position of the thread lock.

In testimony whereof I have affixed my signature, in presence of two witnesses.

HARRIE A. BALLARD.
